UNITED STATES PATENT OFFICE.

JOSEPH D. ROURK, OF BRIDGEPORT, CONNECTICUT.

ROTARY VALVE.

1,131,089.

Specification of Letters Patent.

Patented Mar. 9, 1915.

Application filed December 13, 1913. Serial No. 806,392.

To all whom it may concern:

Be it known that I, JOSEPH D. ROURK, a citizen of the United States, residing at Bridgeport, in the county of Fairfield and State of Connecticut, have invented certain new and useful Improvements in Rotary Valves, of which the following is a specification.

This invention relates to improvements in valves, and more particularly to valves of that character known as rotary valves, the object of the invention being to provide an improved valve of this character for use in connection with internal combustion engines, steam and water pumps, etc., for the admission and exhaust of liquids, gases and exhaust vapors, and to provide improved means for rotating said valve by means of the reciprocations of the piston or other reciprocating part of the engine or pump.

In the drawings accompanying and forming part of this specification, Figure 1 is a sectional side view of the cylinder and part of the crank case of a water-cooled internal combustion engine provided with my improved rotary valve, the latter being shown in side elevation; Fig. 2 is a horizontal sectional view taken on line 2—2, Fig. 1, and showing the passage or channel through the valve head in register with the cylinder opening for the admission of gas into said cylinder; Fig. 3 is a sectional view of the valve stem and showing its connection with the piston of the engine, said piston being shown broken away; and Fig. 4 is a sectional view of the valve stem taken on line 4—4, Fig. 1.

Similar characters of reference indicate corresponding parts in the different figures of the drawings.

In the present instance the improved rotary valve is shown in connection with an internal combustion engine, the cylinder 2 of which is suitably mounted on the crank case 3 and is provided with a water jacket 4. In a lateral extension 5 of the cylinder are located an inlet port 6 and an outlet port 7, both of which are in communication with a port or passageway 8 leading into the cylinder, such cylinder having the usual piston 9, piston rod 10 and crank pin 11 for connection with the crank shaft. Within the lateral extension 5 of the cylinder, at the junction point of the ports 6, 7 and 8, is located a valve seat for the reception of this improved rotary valve, which comprises in the

present instance a valve head 12, shown herein as of conical or tapered formation, which valve head is provided with a port or channel 13 therethrough so formed that when the valve is rotated to a certain position the port 13 therein will communicate with the inlet port 5 and the port 8 leading to the cylinder, and when the valve is rotated to another position the port 6 will be closed and the port 8 placed in communication with the outlet port 7, and when the valve is rotated to still another position all three of the ports 6, 7 and 8 will be closed. The valve head 12 is provided with a stem or extension 14 having an enlarged cylindrical portion 15, provided with a plurality of lengthwise extending grooves 16, four being shown in the present instance, the alternate grooves being slightly spiral in opposite directions so that the end of a preceding groove merges with the beginning of the next succeeding groove, thereby completely encircling the valve stem 15. The crank case 3 is provided with an opening 17 for receiving the end of the valve stem 15 and closely encircling the same.

For the purpose of permitting the adjustment of the valve head to its seat and thereby take up any wear that may occur, and also to provide a bearing for the end of the valve stem, the crank case 3 is provided with a bracket 18 projecting inwardly thereof a suitable distance below the opening 17, said bracket having an upturned end 19. On this bracket 18 is mounted a pair of wedge shaped members 20 and 21, placed one on top of the other, the upper member 21 being reversed and having its wedge face placed adjacent to the wedge face of the member 20 and provided in its opposite side with a suitable bearing for the end 22 of the valve stem 15. A set screw 23 is threaded in an opening in the side of the crank case directly opposite the thicker end of the member 20, with its end in contact with such member, and by turning this screw, as will be readily seen, the valve head can be adjusted to take up any wear between it and its seat.

For the purpose of rotating the valve, a bar or rod 24 is provided, one end thereof passing through a slot 25 extending lengthwise of the cylinder and securely fastened to the end of the piston, as at 26, for reciprocation therewith. This bar 24 is provided just outside of the cylinder wall, with an enlarged portion or shoulder 27, and the

outer edges of the slot 25 are suitably rabbed, as at 28, to receive such shoulder and form a guideway therefor during its reciprocatory movements with the piston, thereby preventing any side thrust to the piston. The opposite end of the rod 24 is of yoke formation, as shown at 29 in Fig. 3, and partly encircles the valve stem 15. Each end of the yoke is adapted to receive a stud 30, having a roller 31 mounted thereon in position to engage one of the grooves 16 in the valve stem 15, thereby to rotate the valve on the reciprocation of the piston. Between each of the rollers 31 and the end 15 of the yoke 29 carrying the same is a coiled spring 32, and the grooves 16 are so formed that the beginning of each succeeding groove is deeper than the end of the preceding groove, in other words the bottoms 20 of the grooves are inclined so that each groove is deeper at its beginning than at its end, and therefore as the reciprocation of the piston brings the rollers to the end of each groove the spring pressure on such 25 rollers forces them to engage the next succeeding groove instead of permitting it to return in the same groove, thereby insuring the proper continuous rotation of the valve in the same direction.

30 The operation of the valve is as follows: The reciprocation of the piston rotates the valve, by reason of the engagement of the rollers 31 with the grooves on both sides of the valve stem, and brings the channel 35 or port 13 of the valve head into communication with the port 8 in the cylinder and the inlet port 6, thus admitting gas from the carbureter (not shown), into the cylinder. On the next stroke of the piston the 40 valve is rotated one fourth of a revolution, and this shuts off communication between the port 8 and the inlet port 6, and the port 8 remains closed during the next two reciprocations of the piston, during which time 45 compression and ignition is taking place within the cylinder, and on the next or fourth reciprocation of the piston the valve is rotated so as to bring the port 13 into position to communicate with the port 8 and 50 the outlet port 7, which completes the rotation of the valve. On the next stroke of the piston the outlet port is closed and the inlet port again brought into communication with the port 8, and so on. It will thus be seen 55 that while the rotation of the valve is continuously in the same direction,—that is, there is no backward movement,—such rotation is intermittent, since at the end of each stroke of the piston there is a certain 60 period during which the valve is stationary until the piston has advanced sufficiently far to bring the rollers into operative engagement with the sides of the next succeeding pair of grooves, thereby affording sufficient 65 time for the explosive gas to enter the cyl-

inder and the proper exhaustion thereof after explosion when the port 13 is in communication with the ports 6 and 7 respectively.

It is to be understood that while I have shown this improved valve arranged for use in connection with an internal combustion engine, it may be adapted for many other purposes, such as in connection with steam or water pumps for the admission and outlet of gases and liquids, and while I have shown the piston as the most convenient instrument for causing the rotation of the valve I do not confine myself to this means of rotation, but the valve may be rotated by connection with any reciprocating part. It is also to be understood that the details of construction may be varied to suit the different purposes to which it may be put without departing from the spirit and scope of this invention.

I claim as my invention:

1. The combination with a cylinder and a reciprocatory member, of a rotary valve located outside of said cylinder and having a 90 stem substantially parallel with said reciprocatory member, and means reciprocating with said reciprocatory member and coöperating with said valve stem for rotating said valve on the reciprocation of the reciprocatory member.

2. The combination with a cylinder having a reciprocatory piston therein and a lateral extension forming a valve seat, of a rotary valve located in said seat and having an 100 enlarged portion extending in substantial parallelism with said piston, and means carried by said piston within the cylinder and coöperating with said enlarged portion for rotating the valve on the reciprocation of 105 said piston.

3. The combination with a cylinder having a lateral extension forming a tapered valve seat located exteriorly of the cylinder, of a rotary valve located in said seat, a reciprocatory piston in said cylinder, and connecting means extending through the side wall of said cylinder and adapted to impart 110 rotary motion to said valve on the reciprocation of said piston.

4. The combination with a cylinder having a lengthwise extending slot and provided with means for the reception of a valve seat, and a reciprocatory piston within said cylinder, of a rotary valve comprising a head located in said seat, a valve stem provided with a plurality of oppositely extending spiral grooves, and a rod secured to said piston and extending through the slot in said cylinder and having a projection 123 adapted to enter said grooves thereby to rotate the valve on the reciprocation of said piston.

5. The combination with a cylinder having a lengthwise extending slot, and pro-

- vided with means for the reception of a valve seat, of a rotary valve located in said seat, and adapted to close said port, a valve stem connected to said valve and provided 5 with a plurality of oppositely extending spiral grooves, a reciprocatory piston in said cylinder, and a rod connected to said piston and extending through the slot in said cylinder and having at its opposite end a yoke-shaped member provided with rollers for 10 engaging a pair of said grooves thereby to rotate said valve on the reciprocation of said piston.
6. The combination with a cylinder having 15 a lengthwise extending slot, and provided with means for the reception of a valve seat, of a rotary valve located in said seat, a valve stem connected to said valve and provided with a plurality of oppositely 20 extending spiral grooves, a reciprocatory piston in said cylinder, and a rod connected to said piston and extending through the slot in said cylinder and having at its opposite end a yoke-shaped member provided 25 with rollers for engaging a pair of said grooves thereby to rotate said valve on the reciprocation of said piston, each of said grooves being deeper at one end than at the other.
- 30 7. The combination with a cylinder having a reciprocatory piston therein and provided with means for the reception of a valve seat, of a rotary valve located in said seat and provided with a solid stem, an adjustable bearing for the opposite end of said 35 stem from said valve, and connecting means between said piston and valve stem for rotating the latter on the reciprocation of said piston, said connecting means extending 40 through the side wall of the cylinder.
8. The combination with a cylinder having 45 a reciprocatory piston therein, of a valve located outside of said cylinder and having a part thereof provided with grooves, and reciprocating means connected with the piston and having a part engaging said grooves for operating the valve on the reciprocation of the piston.
9. The combination with a cylinder having 50 a lengthwise extending slot and provided with means for the reception of a valve seat, and a reciprocatory piston within said cylinder, of a rotary valve having an extending solid stem provided with oppositely 55 extending spiral grooves, an adjustable wedge-shaped bearing for the end of said stem, a connecting member extending through said slot and having one end secured to said piston and its opposite end 60 bifurcated to embrace said stem, and a spring pressed roller on each arm of said bifurcated end for engagement with one of said grooves.
10. The combination with a cylinder having 65 a lengthwise extending slot and pro-
- vided with means for the reception of a valve seat, and a reciprocatory piston within said cylinder, of a rotary valve comprising a head located adjacent to said cylinder and an extending solid stem provided with 70 grooves, a connecting member extending through said slot and having one end secured to said piston and its opposite end in engagement with one of said grooves for imparting motion to said valve on the reciprocation of said piston.
11. The combination with a cylinder having 75 a reciprocatory piston therein, of a rotary valve located outside of said cylinder and having a part thereof provided with 80 lengthwise extending grooves, and reciprocating means connected with a part of said piston and having a part engaging said grooves for rotating the valve on the reciprocation of the piston.
12. The combination with a piston casing 85 and a reciprocatory piston within said casing, of a rotary valve outside of said casing and located at one side of said piston, and means projecting through said casing and movable with the piston and having connection with the rotary valve for rotating said valve on the reciprocation of the piston.
13. The combination with a piston casing 90 and a reciprocatory piston within said casing, of a rotary valve outside of said casing and located at one side of said piston, and means projecting from said valve transversely of the casing and movable with the piston for rotating said valve on the reciprocation of the piston.
14. The combination with a casing having 95 a piston cylinder and a valve seat, of a reciprocatory piston within said cylinder and an axially movable valve in said seat, said valve having a stem located in parallelism with the piston and outside of the cylinder, and reciprocatory, non-rotatable means reciprocable with the piston and having connection with said stem for turning the valve axially in its seat.
15. The combination with a casing having 100 a piston cylinder and a valve seat, of a reciprocatory piston within said cylinder and an axially movable valve in said seat, said valve having a stem located in parallelism with the piston and outside of the cylinder, and reciprocatory, non-rotatable means reciprocable with the piston, said means and stem having one grooves and the other projections cooperating with said grooves for turning the valve axially in its seat.
16. The combination of a power cylinder 105 having a piston reciprocating therein, with a valve located outside of said cylinder for controlling the intake and exhaust gases, the valve embodying an extension provided with cam grooves, together with means actuated by the piston and engaging the 110
- 120
- 125
- 130

grooves whereby the reciprocating movement of the piston imparts a turning movement to the valve.

17. An explosive engine comprising a cylinder having a recess in its side wall, with a revoluble valve for controlling the intake and exhaust of gases and having a stem, a member carried by the piston passing through said recess and engaging said stem, whereby the reciprocating piston imparts an intermittently turning movement to the valve during operation of the mechanism.

18. An explosive engine comprising a power cylinder having a recess therein, the piston of the cylinder being provided with a laterally extending member passing through the recess, a valve for controlling the intake and exhaust of gases, said valve being provided with an extension having zigzag grooves engaging said laterally extending member, whereby a reciprocating movement of the piston imparts an intermittently turning movement to said valve.

19. An explosive engine embodying a power cylinder with a reciprocating piston therein, a power element driven by the piston, and a revoluble valve element at one side of the cylinder for controlling the admission of gas thereto and the exhaust of gas therefrom and operatively connected with the piston independently of said driven element, the movement of the piston imparting a turning movement to the said valve element.

20. An explosive engine comprising a power cylinder having a reciprocating piston therein, a power element driven by the piston, the cylinder being provided with a port, a revoluble valve at one side of the cylinder and having openings therein adapted to register at determined intervals with said port, said valve being in communication with a source of supply and a medium to receive the exhaust at determined intervals, and means independent of said power element engaging the piston and also engaging said valve whereby the movement of the piston imparts independent movement to said valve.

21. An explosive engine comprising a power cylinder, the piston of the cylinder being provided with a laterally extending member, a valve at one side of the cylinder for controlling the intake and exhaust of gases, said valve having a longitudinal extension provided with zig-zag grooves in which the said laterally extending member engages, whereby the reciprocation of the piston imparts a turning movement to said valve.

22. An explosive engine comprising a cylinder having a recess in its side wall, a revoluble valve having a stem for controlling the intake and exhaust of gases, and means carried by the piston passing through said

recess and engaging the stem of said valve, whereby the reciprocation of the piston imparts a turning movement to said valve during operation of the engine.

23. The combination of a power cylinder 70 having a piston reciprocating therein, a valve for controlling the intake and exhaust gases, said valve having a stem provided with a cam groove, said cylinder being provided with a recess, and a member carried 75 by the piston passing through said recess and engaging the said groove, whereby the back-and-forth movement of the piston imparts a turning movement to the valve.

24. An explosive engine embodying a power cylinder having a piston therein, a power element driven by the piston, and a valve at one side of the cylinder and commanding communication with the cylinder and controlling the admission of the charge 80 thereto and the exhaust of the explosive gases therefrom, said valve being operatively connected with the piston independently of said driven element, to actuate said valve.

25. The combination with a cylinder having a reciprocating piston therein, of a valve at one side of the cylinder and having an extension thereof provided with grooves, reciprocating means connected with the piston and having a part engaging said grooves for operating the valve on the reciprocation of the piston, and means for directing the travel of said groove-engaging part from one groove into the next succeeding groove. 90

26. The combination with a cylinder having a reciprocating piston therein, of a valve at one side of the cylinder and having a stem provided with grooves, reciprocating means connected with the piston and having 105 a part engaging said grooves for operating the valve on the reciprocation of the piston, and coöperating means carried by said grooves and groove-engaging part for directing the travel of the latter from one 110 groove into the next succeeding groove.

27. The combination with a cylinder having a reciprocating piston therein, of a valve having a stem provided with grooves, the end of each groove adjacent to the end of 115 its preceding groove being deeper than the opposite end, reciprocating means connected with the piston and having a part engaging said grooves for operating the valve on the reciprocation of the piston, and a spring 120 carried by said groove-engaging part for pressing the latter into the deeper end of each succeeding groove.

28. The combination with a cylinder having a lengthwise extending slot and provided with means for the reception of a valve seat, of a rotary valve located in said seat, a valve stem connected to said valve and provided with a plurality of oppositely extending spiral grooves, a reciprocatory 130

piston in said cylinder, a rod connected to said piston and extending through the slot in said cylinder and having at its opposite end a yoke-shaped member provided with 5 rollers for engaging a pair of said grooves thereby to rotate said valve on the reciprocation of said piston, and coöperating means carried by said grooves and yoke-shaped member for directing the travel of said rollers from one pair of grooves into the next 10 succeeding pair.

29. The combination with a cylinder having a lengthwise extending slot and provided with means for the reception of a 15 valve seat, of a rotary valve located in said seat, a valve stem connected to said valve and provided with a plurality of oppositely extending spiral grooves, the end of each groove adjacent to the end of its preceding

groove being deeper than the opposite end, 20 a reciprocatory piston in said cylinder, a rod connected to said piston and extending through the slot in said cylinder and having at its opposite end a yoke-shaped member provided with rollers for engaging a 25 pair of said grooves thereby to rotate said valve on the reciprocation of said piston, and springs carried between said yoke-shaped member and rollers for pressing the latter into the deeper ends of each succeeding 30 pair of grooves.

Signed at Bridgeport, in the county of Fairfield and State of Connecticut, this 9th day of December, 1913.
